COMBINATION BRUSH AND SCRAPER

Wiley M. Whitaker, Asheboro, N.C., assignor to Whit Corporation, Asheboro, N.C.

Filed July 27, 1970, Ser. No. 24,137

Term of patent 14 years

Int. Cl. D4—01

U.S. Cl. D4—6

FIG. 1

FIG. 3

FIG. 1 is a front elevational view of the combination brush and scraper of my invention;

FIG. 2 is a right side elevational view of the combination brush and scraper of FIG. 1; and

FIG. 3 is a cross-sectional view taken along line 3—3 of FIG. 2.

I claim:

The ornamental design for a combination brush and scraper, as shown.
